CARD FOR SEQUENCE SORTING

Albert A. Rembold, San Francisco, Calif.

Application November 5, 1948, Serial No. 58,494

4 Claims. (Cl. 129—16.1)

1

This invention relates to cards, flat sheets and the like (hereinafter called cards) for classification purposes and for sequence sorting that are similar to the card shown in my United States Letters Patent No. 2,424,053 of July 15, 1947.

Cards herein disclosed are formed adjacent one or more edges thereof with coded openings or perforations, one or more of which are slotted out to the edge of the card to provide a notch or pattern of notches identifying the card. The openings in all cards are arranged to register with each other when the edges of the cards are aligned in a stack or row, so that a separating needle or rod thrust through one set at a time of any sets of registering openings, and then lifted, will carry with it all cards in which said openings are not slotted out, but the card or cards, in the said set of openings, that are slotted out to the edge, will fall from the elevated stack.

It is understood that the stack referred to above extends horizontally so that the cards themselves are substantially vertical.

The method employed for sequence sorting is old, and the general structure employed is old. Prior to my disclosure in the above mentioned patent, the openings to be slotted out were arranged in one, two or three rows parallel with an edge of each card. These rows were divided into "fields" and these fields usually have had the same number of openings in each with code symbols, usually numbers, identifying the openings in each field. The fields in series from one end of the rows to the other have been usually identified for "units," "tens," "hundreds," "thousands," etc., being limited only by the length of the card or the extent to which the numerical classifying system may be required.

In my above mentioned patent, an arrangement was shown in which only four openings were required in each field, being arranged two wide and two deep, and by this arrangement the space that was formerly required for accomplishing the same result was reduced by a third, thus permitting a very great extension of the data-capacity of each card without increase in the size of the card, or else the size of the card could be greatly reduced without sacrifice in the amount of data thereon.

In order to obtain the desired results in the card shown in said patent, it was necessary to slot out an opening in one or more fields in certain cards at an angle to the adjacent edge of the card. While this offered no particular problem for hand punching, it was discovered that by a slight repositioning of the four openings in

2

each field, overcame the problem of slotting out the openings with faster quantity punching apparatus, and that the slotting out by hand punches was accomplished more accurately and easily.

One of the objects of this invention is the provision of a card having openings in the fields so arranged that diagonal or slanted slotting out of the desired opening or opening in each field may be accomplished accurately and easily and without objectionable loss in the strength of the card when the sorting operation is being done.

Another object of the invention is a different arrangement of the openings in each field in selective sorting cards of the type shown in my previously mentioned patent whereby faster and more accurate diagonal slotting out of one or more of the openings in the fields may be accomplished without objectionably weakening the card and without loss in the results and advantages thereof.

In the drawings, Fig. 1 is a plan view of a card that is illustrative of the invention.

Fig. 2 is a fragmentary plan view of a card having a different pattern of notches from that shown in Fig. 1.

In detail, each card 1 is provided with a row of openings 2 close to an edge thereof and parallel therewith, while a second row of openings 3 is parallel with said edge but spaced slightly farther therefrom. Thus, a pair of parallel rows of openings is adjacent one edge 1 of the card. It is obvious that a pair of rows of such openings may be along any of the other edges of the card, if desired; and usually such row is along one or more of such other edges.

The openings in these rows are the same in number, but in row 3, every other opening 4 of row 3 is slightly offset toward row 2 and also is closer to one of the adjacent openings at one side thereof. Also each opening 4 is preferably smaller than the other openings, while the latter are of uniform size.

The openings 5 in row 3 other than openings 4 are in alignment with an adjacent opening 6 in row 2 at right angles to the adjacent edge of the card.

It is to be understood that invention is not limited to the precise dimensions of the openings, but as an example, the openings 4 may each be about .005 of an inch less in diameter than the diameter of each of the remaining openings, while the remaining openings may each have a diameter of about .092 inches. Six of these open-

ings in each row may be in each inch extending longitudinally of the row.

The offset of each opening 4 in one direction longitudinally of row 3 may be only about half the diameter of each opening 4 and about the same degree of offset is toward row 1, or about .04 of an inch of the size of the openings is that given above.

The openings in the rows are divided by lines 10 into fields of four openings in each field. One of the openings 4 is in each field and openings 4 are each similarly positioned in each field.

The openings in row 2 in each group may be identified by the numerals "1," "3" which numerals may be printed adjacent said openings if desired. The openings in row 3 in each group may be identified by the numerals "7" and "2."

Following the usual practice of slotting out such openings singly or in combinations of two, it will be clear from Figs. 1, 2 that all digits from one to nine are readily obtained by directly slotting out openings in either row 2 or row 3 directly to the edge 1 except in the case of the digit "6." The card shown in Fig. 1 has the openings slotted out for identifying the card as Card No. 62,371, while the card of Fig. 2 has its openings slotted out for identifying the card as No. 590,468. Thus the "ten thousand" field of the card of Fig. 1 and the "ten" field of Fig. 2 must each make provision for the digit "6," which has been done by diagonally slotting out the opening for designating the digit "7" through the opening for identifying the digit "1."

In the type of notching shown in the drawings, the card having the diagonal slotting will drop from the stack when a needle is thrust through the holes identifying the digit "7," and in a sequence sorting operation the cards bearing the digit 6 anywhere in their combination will be in correct order after said operation is performed.

The sorting for one field from "0" to "9" will be described, it being assumed that the stack of cards are numbered from "0" to "9." Inasmuch as resort must be had to a second field in order to obtain the numeral "10," the operation will be restricted to one field, which field may be considered as the field designated "units" on the card.

The sorting needle or pin is first thrust through the opening identified by the numeral "1" and upon lifting the needle the cards identified as "0," "3," and "7" will be retained on the needle while the cards identified as "1," "2," "4," "5," "6," "8," and "9," will drop therefrom.

The cards retained on the needle are then removed therefrom and those that were released are placed in the rear of the stack or row. The needle is then inserted through the openings designated "2," thereby freeing cards identified as "2," "5," and "9," which latter cards are placed at the rear of the stack and the needle is then thrust through the openings designated "3" for freeing cards identified as "3," "4," "5," "7," "8" and "9." These latter cards are placed at the rear of the row. The operation performed with the needle in the openings designated 7 will result in freeing the cards designated "6," "7," "8" and "9," and at this point it is to be noted that the card designated "6" will be just ahead of the one designated "7" and all cards will be in sequence, it being understood that the above released cards "6," "7," "8," and "9" are placed at the back of the stack or row.

In a zone indicated at 11 are two openings 12 that may be employed for use in sorting cards where a zero is involved in the identifying num-

ber, but this is no part of the present invention.

The conventional punch employed for slotting out one of the openings in row 3, one of which slots is indicated at 13 in Fig. 1 is not adapted for making the diagonal slot 15 (Fig. 1). However, by positioning the openings 4 nearer to row 2 and to the opening 5, and by making openings 4 slightly smaller in diameter than the other openings, the openings 4 may readily be slotted out by swinging the punch about a point adjacent the nearest edge of the card so that the outer end of said punch will cut out the opening 4 without objectionably weakening the card. Furthermore, the slotting out of the openings 4 in directions at right angles thereto, as seen at 14, will not cause any objectionable weakness.

It may be noted that the punch for slotting out the openings need not necessarily extend to the closed side of the opening that is opposite the side that is to be slotted out. Also, a hand punch may be readily used for punching out the holes.

I claim:

1. A card for classification purposes having a first row of uniform diameter equally spaced openings formed therein along one edge parallel therewith, a second row of openings formed in said card, alternate openings in said second row being in alignment with a corresponding opening in said first row in direction perpendicular to said edge and the other openings in said second row between said alternate openings being offset in one direction longitudinally of said second row and also offset toward said first row distances respectively less than the diameter of the openings in said first row the openings in said first and second rows being grouped in series of four approximating a square with the offset opening in each of said series of four being in the perimeter of the square opposite said edge.

2. A card for classification purposes having a first row of uniform diameter equally spaced openings formed therein along one edge parallel therewith, a second row of openings formed in said card, alternate openings in said second row being in alignment with a corresponding opening in said first row in direction perpendicular to said edge and the other openings in said second row between said alternate openings being offset in one direction longitudinally of said second row and also offset toward said first row distances respectively less than the diameter of the openings in said first row, the said openings in said first row and in said second row being arranged in groups of four with one of said offset openings being in each group and in the same relationship to the other openings in each group the openings in said first and second rows being grouped in series of four approximating a square with the offset opening in each of said series of four being in the perimeter of the square opposite said edge.

3. A card for classification purposes having a first row of uniform diameter equally spaced openings formed therein along one edge parallel therewith, a second row of openings formed in said card, alternate openings in said second row being in alignment with a corresponding opening in said first row in direction perpendicular to said edge and the other openings in said second row between said alternate openings being offset in one direction longitudinally of said second row and also offset toward said first row distances respectively less than the diameter of the openings in said first row, the said openings so

offset being slightly smaller in diameter than the openings in said first row the openings in said first and second rows being grouped in series of four approximating a square with the offset opening in each of said series of four being in the perimeter of the square opposite said edge.

4. A card for classification purposes having a first row of uniform diameter equally spaced openings formed therein along one edge parallel therewith, a second row of openings formed in said card, alternate openings in said second row being in alignment with a corresponding opening in said first row in direction perpendicular to said edge and the other openings in said second row between said alternate openings being offset in one direction longitudinally of said second row and also offset toward said first row distances respectively less than the diameter of the openings in said first row, one of the open-

ings so offset being slotted out to the adjacent edge of said card through one of the openings that is in alignment to said edge with the opening in said second row that is adjacent the said offset opening, the openings in said first and second rows being grouped in series of four approximating a square with the offset opening in each of said series of four being in the perimeter of the square opposite said edge.
